CONNECTOR UNIT FOR ELECTRIC WIRING SYSTEMS

Joseph F. O'Brien, Jersey City, N. J., assignor to
 John B. Pierce Foundation, New York, N. Y., a
 corporation of New York

Application January 11, 1941, Serial No. 374,059

4 Claims. (CL 173—324)

The present invention relates to electrical wiring devices.

In particular, the invention relates to a novel connector device for use with an electric wiring system in which conductor-containing units are arranged in seriatim electrical and mechanical interconnection and positioned, for example, at the base board of a room or the like.

The present invention has for an object, the provision of a universal angle connector for such conductor-carrying units, said connector unit comprising elements which may be molded from plastic materials and readily assembled by unskilled labor.

It is a further object of the invention to provide a connector unit having pivotally secured branches, each branch being adapted for connection with a conductor-containing unit, and providing means whereby the angular relationship of one of said conductor-containing units with respect to the other may be altered to provide for the continuous run of the unit about an angularly offset building wall, for example, regardless of the degree of such angular wall offset.

It has previously been proposed to provide angular connectors for the units of such a wiring system, but such angular connectors have been of fixed angular relationship, usually a right angle relationship. It will be apparent that in the run of a system of seriatim-interconnected conductor units around a room, two types of corner units will be required, to accommodate an "inside" corner at the junction of the principal walls of the room, and an "outside" corner to accommodate offsets or bays within the room. Additionally, all of the corners of a room may not be precisely at right angles. The fixed-angle corner connectors, therefore, must be made in both "inside" and "outside" types, thus adding to the amount of stock necessary for the contractor to have on hand, with attendant inventory difficulties and increased capital outlay.

In the present invention, means are provided whereby a single form of connector is adjustable for both "inside" and "outside" angle service. Additionally, the angular relationship of the branches of my improved connector unit is readily adjusted, to conform to wall angle relationships which may not be rectangular.

Other features and advantages will hereinafter appear.

In the drawings:

Fig. 1 is a perspective of a portion of a room, showing a typical installation of my invention;

Fig. 2 is a plan view of a form of the present

invention, illustrating the variant angular relationships attainable therewith;

Fig. 3 is an enlarged sectional elevation, taken on lines 3—3 of Fig. 2;

Fig. 4 is a plan section, taken on lines 4—4 of Fig. 3;

Fig. 5 is a sectional elevation, taken on lines 5—5 of Fig. 3;

Fig. 6 is a sectional elevation, taken on lines 6—6 of Fig. 3;

Fig. 7 is a sectional elevation, taken on lines 7—7 of Fig. 3;

Fig. 8 is an exploded perspective of one of the branch elements of my invention;

Fig. 9 is a perspective of the housing component of the unit of Fig. 8, showing an arrangement of internal supporting means;

Fig. 10 is an exploded perspective of the complementary branch element; and

Fig. 11 is a perspective of one of the electricity conductors of the Fig. 10 component branch element.

Referring to Fig. 1, so much of a room is shown as is required to illustrate an application of the present invention. In such room, an electricity conductor system is arranged on the top edge of a base board 10, and said electricity conductor system includes units 11, 11, 11, interconnected by the universal angle connector devices 12, 12, pursuant to the present invention. As appears, said connection devices 12, 12, may be arranged to form either an "outside" or an "inside" angle, according to the relationship of the walls of the room, and it is clearly apparent from Fig. 2 that any required angular relationship of the branches of said universal angle connector may be attained.

Desirably, the electricity conductor units 11 may be of the type described and claimed in the presently co-pending application of Louis G. Morten and Joseph F. O'Brien, Serial No. 356,844, filed September 14, 1940, issued as Patent No. 2,239,652 on April 22, 1941, a feature of such unit being that each end of such units has, respectively, a male and female configuration whereby conductor units or connecting devices therefor may be assembled in a seriatim electrical and mechanical connection, with access to the internal conductors of the units precluded by the interfitting of the male formation of one unit with the female formation of the adjacent unit.

For suitable seriatim connection with such male and female end portions of a unit 11 or equivalent, one branch member of the connector unit 12 may be formed with a male end portion

14, and the other branch member with a female socket portion 15, as later more fully described. For convenience in designation, the respective branches will be hereinafter referred to as the male branch 16 and the female branch 17, respectively. It is preferable to form these branch members of suitable moldable plastic materials.

Referring to Figures 4 and 8, the female branch 17 includes a central conductor carrier 18, electricity conductor elements 19, 19, arranged to be supported thereon, and a housing 20 within which the carrier 18 and its therewith associated conductors 19, 19, may be inserted and suitably fixedly secured as by the illustrated rivets 21. An end portion of said housing cooperates with the central body member to form the socket 15, as shown in Fig. 3.

The electricity conductors 19, 19, see Fig. 8, are desirably formed from relatively heavy sheet brass or the like, and have a body 22 and a head 23, joined by a relatively short neck 24. Extending lugs of the body portion 22 may curve about a tubular conductor 25, and be rigidly secured thereto in electricity conductive relationship by soldering or brazing. Suitable apertures 26, 26, and 27 are provided in the body portion 22 and the disc-like head 23, respectively.

The conductor carrier 18 has a rounded head 28 of substantial depth, projecting forwardly of and at one side at least, offset with respect to an integral body portion 29. Centrally of said head 28, and on each of the principal faces thereof, is formed a suitable depression, each characterized by a step 30 and an annular rim 31. The base of each such depression is in a plane common to the corresponding face of said body portion 29, the ends of such body portion faces being defined by upstanding wall formations 32, 32, and a side thereof, by a wall 33. Annular wall formations 34, 34, are molded on each of said body member faces. From the foregoing, it will be understood that the configuration of the conductor carrier 18 is identical on each of its principal faces. The apertures of said annular formations 31, 34, 34 extend completely through the conductor carrier 18.

The conductors 19 fit within the conductor carrier 18, the diameter of the head portion 23 of the conductor being equal to the minimum diameter of the depressed head portion, and the diameter of the aperture 27 of said conductor head being equal to the outside diameter of the annular portion 31. Likewise, the length of the body portion 22 of the conductor is preferably equal to the distance between the end walls 32, 32 of the body member 29 and the apertures 26 and the diameters thereof are in registry with and equal to the diameters of the annular elements 34 of said body. The thickness of the body 22 and head 23 of the conductors 19 is preferably equal, respectively, to the height of the walls 32 and the distance from the base of the head depression to the step 30 thereof. Thus, the conductors 19 fit snugly within the conductor carrier 18. Suitable accommodation is made for those portions of the conductor body 22 which curve about the tubular conductor 25, and said tubular conductor 25 of each of the conductors 19 rests within a cradle formation 35 in the end wall 32 of the conductor carrier 18.

Referring now to the housing member 20, one end is formed with walls 36 establishing the female socket portion of female branch 17. The length of the body 29 of the conductor carrier 18, measured rearwardly from the offset 37 of the

head 28 is equal to the distance from the face 38 of the housing 20 to the offset 39 which defines the limit of the wall 36. The thickness of said body 29 measured at the walls 32 thereof is equal to the width of the slot 40 of the housing member 20. The total height of the wall 33 of said conductor carrier 18 is equal to the height of the opening 20a of the body member 20, see Fig. 5, and the length of such wall 33 is equal to the distance from the inner surface of face 36 to the offsets 39 of the housing 20. Additional supporting devices within the body 20 are provided by the upstanding wall formations 41, 42.

The maximum width of the head portion 28 is equal to the maximum width of the body 20. It will be seen, therefore, that when the conductor carrier 18 and its positioned conductors 19 are slidably inserted into the housing 20, the side wall 33 completes the side closure of the housing 20 and the rearmost wall 32 cooperates with the upper and lower wall 42 of the housing to complete the rear wall formation of the female socket. The head 28 projects forwardly from the housing, and forms an extending tongue for hinge-like connection with the male branch 16 of the complete unit 12, as presently described. The conductor carrier 18 is secured by the rivets 21, aforesaid, and the respective wall members 41, 42, of said housing 20 lie in contact with the surfaces of the conductors 19 and hold such conductors against displacement.

The male branch 16, see Figures 3 and 10, may include a central member 63 and cover members 64, 64. Within each of said cover members 64 is secured, as during the molding stage of said members 64, an electricity conductor element 65. The central member 63 and the cover members 64, 64, are arranged to be integrated into a unitary structure by such means as the rivets 66, Fig. 4.

Referring now to Figs. 10 and 11, the conductors 65 are preferably embedded within the elements 64, 64 during the molding stage thereof. Each conductor includes a preferably tubular element 61, suitably secured to a wall formation 68 which may be integral with a circular head 69. As shown in Fig. 10, the head 69 is embedded in, and surrounded by a rim 70 of the insulation material of which element 64 is formed, and a central annular wall 71 is in contact with the internal edge of such head 69.

The opposite end of each member 64 is formed with a wedge-like projection 72 for ultimate cooperation with the female socket portion of a conductor unit 11, as suggested by the broken line of Fig. 3.

The central member 63 is provided with suitable grooves on each of its principal faces to accommodate such portions of the tubular conductor 65 and the wall 68 as extend upwardly from the surface of the respective members 64, 64. As Fig. 8 shows, the member 63 has a wedge-like terminus 73; the length of such member 63 up to the commencement of said wedge 73 is equal to the length of the corresponding portions of the elements 64. When the elements 64 and the central member 63 are assembled, there remains a mouth extending forwardly of the front wall 74 of member 63, the maximum opening of which is equal to the thickness of the head 28 of the female branch 17. It will be noted, however, that there is a circular plateau on the surface of each of the body members 64, caused by the head 69 of the conductor 65 and the annular shoulder 70 surrounding such head 69. The outer

diameter of said plateau is equal to the maximum diameter of the depression in the head 28, and the depth of said plateau is equal to the depth to the offset shoulder 30 in said head 28. Accordingly, the surface of the annular rim 70 rests upon the offset 30 of said head 28, and it will be seen that the head 28 must be positioned between the body elements 64, 64, before said body elements are secured, as by the rivets 66, to complete the assembly with the central body member 63. Such interfitting relation of the head 28 and the body elements 64, 64, tends to maintain the hinge relationship of said respective members, and such hinge relationship is secured by a suitable pin or rivet 76, see Fig. 3. The annular rim 70 and its position within the depression of head 28 provides insulating walls which preclude ingress of water or the penetration of a knife blade or the like which might otherwise contact the conductor portions 69 and/or 23 from without.

As Figure 5 indicates, the annular shoulders 34 of the female branch unit 17 adequately insulate the rivets 21 from the conductors 19, 19; desirably, in both the male and female branches suitable countersinks are provided so that the rivet heads may be flush with the outer surfaces of such branches.

The securing of the respective branches 16 and 17 by the rivet 76 is accomplished in such member that it holds the surfaces of the conductor portions 23 and 69 in tight contact. It is not the purpose of the present invention that the branches 16 and 17 be freely swingable; to the contrary, it is desirable that positive muscular effort be required to alter such angular relationship.

It is a feature of the male and female interconnection of the conductor units or the interconnection of a connector unit 12 with a conductor unit, that the joint between the conductors of such interconnected conductor and connector units is completely enclosed within a wall of insulation material. To this end, the base of each male projection of each connector unit is provided with a foot which is adapted to close the three-sided female socket. In the instant invention, such foot is provided by a wall 75 formed preferably as an integral part of the central element 63 of the male branch 16.

After the respective male and female branches of the unit 12 are assembled as aforesaid, and are pivotally secured by the rivet 76, it is seen from Figure 3 that the respective head portions of the conductors 19 and 65 are in surface contact over a substantial area. Such surface contact remains throughout any angular relationship of one branch with the other and accordingly, continuity of electric circuit is maintained regardless of such angular relationship.

As appears in Figures 4, 5, and 7, the tubular members of each conductor 19 and each conductor 65 are in a common plane; it will be understood that the plane of such tubular conductors is the same as the plane of the conductors in the various conductor units 11. Electrical interconnection of the conductors of a conductor unit 11 and the universal angle connector 12 may be accomplished by the insertion, into said tubular conductors, of an electrically conductive pin, preferably suitably tapered to make a close fit with the inner walls 70 of said tubular conductors.

As indicated in Figure 4, a passage 77 is provided through the wall of the housing 20 at its

socketed portion 15, and a similar passage is provided through the male projection 14 of the male branch 16. The passage in the female socket 15 of the unit 12 is positioned for registry with a similar passage in the male projection of a conductor unit 11, so that when such male projection is inserted into the female socket 15, a continuous passage is provided through which a screw or the like may be passed to secure the units 10 to the wall of a building. Similarly, the passage 77 through the male projection 14 of the unit 12 is positioned for registry with a passage provided through the female socket portion of a conductor unit 11, so that when said male portion is positioned within the female socket portion of a conductor unit, a continuous passage is provided through which a screw or other fastening device may be passed.

It is to be understood that the respective 20 branches of the connector unit 12 are not to be limited to any standardized length. It is preferable, however, to have the overall depth and width of the branches of the connector unit 12 equal to the depth and width of the conductor units 11, so that the interconnection therewith may be without offset or visible break in surface contour.

Whereas I have described my invention by reference to specific forms thereof, it will be understood that many changes and modifications may be made without departing from the spirit of the invention.

I claim:

1. An adjustable angle connector unit for a wiring system, comprising a pair of hingedly joined branches, each branch being adapted for electrical and mechanical connection with a unit of said wiring system, one branch comprising a conductor member having a body and a head extending forwardly thereof, an electricity conductor positioned on each side of said body and having an arcuate contact portion disposed on each side of said head, and a substantially rectangular hollow housing for said body, said housing having an open side and an open end and a slotted end wall to permit the body to be inserted into said housing through the open side thereof, with the head extending forwardly of the housing and the open side of said housing closed by a side wall of the body; a second branch in hinged connection with said first branch and having electricity conductors in slidable contact with the corresponding conductors of said first branch; and means for pivotally securing said branches.

2. An adjustable angle unit according to claim 1, further characterized by the said housing being of greater depth than the said body, and said housing having transverse walls arranged internally thereof to bear against the electricity conductors of said body and secure the same in fixed position thereon.

3. An electricity conductor as recited in claim 1, further characterized by the housing member having a greater length than the body member, whereby on positioning the body member within the housing, the end wall of said body member and the three side walls of the housing form a socket of fixed depth.

4. An electricity conductor as recited in claim 1, wherein the second branch includes body members of insulation material overlying the head member of said first-named branch.

JOSEPH F. O'BRIEN.
